United States Patent Office

Des. 220,672
Patented May 4, 1971

220,672

BOTTLE CAPPER

Iganzio Ronchetti, Via Fratelli Calvi 67,
Calolzio Corte, Italy

Filed Mar. 18, 1970, Ser. No. 21,951

Term of patent 3½ years

Int. Cl. D15—05

U.S. Cl. D94—3

Fig. 1

Fig. 2

Fig. 3

Fig. 4

FIG. 1 is a front elevational view of a bottle capper showing my new design;

FIG. 2 is a rear elevational view;

FIG. 3 is a side elevational view looking from the right of FIG. 1; and

FIG. 4 is a top plan view thereof.

I claim:

The ornamental design for a bottle capper, substantially as shown.
